UNITED STATES PATENT OFFICE.

BERNARD ARTHUR BEHREND, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

MULTIPOLEAR DYNAMO-ELECTRIC MACHINE.

1,071,546.

Specification of Letters Patent. Patented Aug. 26, 1913.

Application filed September 16, 1905. Serial No. 278,807.

To all whom it may concern:

Be it known that I, BERNARD A. BEHREND, citizen of the United States, residing at Norwood, in the county of Hamilton and State of Ohio, have invented certain new and useful Improvements in Multipolar Dynamo-Electric Machines, of which the following is a full, clear, and exact specification.

10 My invention relates to an improvement in dynamo electric machines of the commutator multipolar type and particularly to the brush connections whereby a more uniform distribution of current is obtained over the 15 commutator.

In large dynamo-electric machines of the multipolar type, current is led to and from the armature by a plurality of groups of positive and negative brushes, alternately 20 arranged around the commutator. In a common type of machine each group of brushes is supported by a brush holder frame comprising a stud and two arms, which arms are pivoted to bolts or rods 25 supported on but insulated from arms integral with the large brush yoke. It is customary to connect all the groups of positive brushes together and all the groups of negative brushes together by means of two rings 30 of strap copper, one ring being connected to the positive brushes and the positive lead and the other ring being connected to the negative brushes and the negative lead. Heretofore these two rings have been usually 35 arranged adjacent each other and have been connected to either the inner or outer ends of the bolts or rods which support the brush holder frames. The terms "inner" and "outer", are used here and elsewhere in 40 this specification as convenient terms to denote respectively parts nearer to and farther from the frame of the machine. It has been found when the two connecting rings are both joined to either the inner or outer 45 ends of the bolts, that the current is not equally distributed through the brushes of each group, but the brushes nearer the connecting rings carry more current than the brushes more remote from the connecting 50 rings, the amounts of current carried by the brushes of each group gradually decreasing from the brush nearest the connecting ring to the brush on the opposite end of the stud. Thus one or more of the brushes of each

group are frequently overloaded, which 55 overloading results in considerable sparking and heating of the adjacent portion of the commutator. The result is that the stress in the commutator bars due to heat expansion is unequally distributed. One portion expands at a greater rate than the other with a result that the commutator is twisted or distorted.

Now the object of my invention is to avoid this unequal heating effect by distributing 65 the current equally over the commutator.

In carrying out my invention I arrange the positive and negative brush connecting means to opposite ends of the positive and negative brush studs respectively, in consequence of which both ends of the commutator will be heated substantially equally.

More specifically considered, my invention consists of a dynamo electric machine of the multipolar type having a plurality of 70 alternately arranged groups of positive and negative brushes mounted in brush holders supported on brush holder frames, and separate connecting means for the positive and negative brushes, the two connecting means 80 being connected to opposite sides of the brush holder frames, whereby there will be more equal distribution of current over the commutator and both ends of the latter will be uniformly heated.

85 Referring to the drawings, which embody one form of the invention, Figure 1 is an elevation of a portion of a dynamo electric machine having my invention applied thereto; Fig. 2 is a plan of the same; Fig. 3 is a 90 development of the winding and commutator of an eight-pole machine showing the brushes and the relative arrangements of the positive and negative cross connectors or connecting rings, and Fig. 4 is a sectional 95 view taken approximately on the line 4-4 of Fig. 1.

I have shown at 10 a portion of the field frame of a dynamo electric machine surrounding the armature 11 which is mounted 100 on the shaft 12. Mounted in rollers, one of which is shown at 13, is the large adjustable brush supporting ring or yoke 14. Extending from the brush yoke are the arms 15 in which are secured the horizontal rods or 105 bolts 16. Pivoted to and insulated from the bolts 16 are the frames comprising the arms 17 and the brush holder studs 18. Mount-

ed upon the studs are the brush holders 19 carrying the brushes 20 which bear on the commutator 21. It is to be understood that as many brush holders as desired may be 5 mounted on each stud.

Alternate groups of brushes are adapted to be connected to the positive and negative mains. As I have shown an eight-pole machine, there will be four groups of positive 10 brushes and four groups of negative brushes. The structure of the generator and brush supporting members so far described is old and I claim no novelty therein.

15 The cross connecting rings are shown at 22 and 23 respectively. These rings are arranged at opposite ends of the commutator, instead of being arranged at the same end as is customary. Alternate groups of 20 brushes are connected to the rings 22 and 23 by means of one or the other of the pair of arms 17 and the straps 24, which connect the rings respectively to opposite ends of alternate bolts 16. In Fig. 3 the positive 25 main is shown connected to the outer ring 22 and the positive brushes, and the negative main connected to the inner ring 23 and the negative brushes, though if desired the positive main may be connected to the 30 inner ring 23 and the negative main to the outer ring 22.

The proportions of current carried by the several brushes of each group has been found in practice to depend on the relative 35 distances from the brushes to the cross connecting ring to which the group is connected. For example the outer brush of each group connected to the outer ring carries the greatest amount of current, and the inner 40 brush of the same group carries the least amount, the amounts gradually decreasing from the outer brush to the inner brush. This unequal distribution of current is probably due, to a great extent, to 45 the fact that the electrical resistance between the brushes and their associated cross-connecting ring is least for the brushes nearest the ring and gradually increases to the brushes most remote 50 from the ring. Consequently, for the groups of brushes connected to the outer ring, the sparking and the current density at the commutator surface are greatest under the outer brushes and least under 55 the inner brushes, and the outer end of the commutator surface is heated more than is the inner end thereof. On the other hand, for the groups of brushes connected

to the inner ring, the sparking and the current density at the commutator surface are 60 greatest under the inner brushes and least under the outer brushes, and the inner end of the commutator surface is heated more than is the outer end thereof. Therefore, 65 the average sparking and the average current density at the surface of the commutator is substantially equal at both ends thereof, and substantially uniform throughout the length thereof, and the commutator is heated substantially equally throughout. 70 There is thus less tendency for the commutator bars to twist and to become displaced. A further advantage gained by this arrangement is that there are fewer strains to be guarded against, and consequently less 75 labor and material are required in the construction of the commutator.

What I claim as new and desire to secure by Letters Patent is:

1. In a dynamo electric machine, a commutator, positive brush means extending along the length of said commutator and negative brush means similarly extending, a terminal connected to the outer end of the brush means of one polarity and a terminal 85 connected to the inner end of the brush means of opposite polarity.

2. In a dynamo electric machine, a commutator, a group of positive electrically connected brushes extending along the 90 length of said commutator, a group of negative electrically connected brushes extending along the length of said commutator, a terminal connected to the outer end of said group of brushes of one polarity and a terminal 95 connected to the inner end of said group of brushes of opposite polarity.

3. In a multipolar dynamo electric machine, a commutator, a set of groups of positive brushes and a set of groups of negative brushes the groups being alternately arranged, means extending along the length of said commutator for carrying said groups of brushes said means being electrically connected thereto, a cross connector 10 connected to the outer ends of said brush carrying means for the one set of groups, and a cross connector connected to the inner ends of said brush carrying means for the other set of groups.

In testimony whereof I affix my signature, in the presence of two witnesses.

BERNARD ARTHUR BEHREND.
